GEORGE HERBERT GUYATT, Inventor

By *Taylor & Taylor*

UNITED STATES PATENT OFFICE

GEORGE HERBERT GUYATT, OF WARWICK LANE, LONDON, ENGLAND, ASSIGNOR TO
JOHN WALKER & COMPANY, LIMITED, OF LONDON, ENGLAND

FILE, TEMPORARY BINDER, LOOSE LEAF BOOK AND THE LIKE

Application filed December 20, 1929, Serial No. 415,390, and in Great Britain June 4, 1929.

This invention relates to files, temporary binders, loose leaf books and the like, of the kind comprising two plates of suitable size and shape, in superimposed relation to each other when the device is in its closed position, the upper plate being slidable upon the lower in a longitudinal direction and to some extent in a transverse direction, both plates being provided with two or more prongs the ends 5 of which are adapted to mate or contact when the device is in its closed position, the longitudinal and transverse movement of the upper plate relative to the lower plate being effected by means of two or more pins or 10 studs each engaging a suitably formed cam slot. The object of the present invention is to provide an improved device of this kind which shall be extremely light and strong, and one having the minimum number of parts 15 consistent with the maximum degree of efficiency under all conditions of usage.

A further object of the invention is to provide a construction which shall be equally applicable to binders or loose-leaf books of all 20 sizes and capacities.

The present invention consists in a file, temporary binder, loose-leaf book, or the like, of the kind first above referred to wherein the cam slots are formed in the upper slideable 25 plate and the coating pins or studs are fixed by riveting or otherwise to the lower plate or plates.

The invention also consists in a device set out in the preceding paragraphs wherein the 30 plates are provided with prongs formed integral therewith.

Further features of the invention will be apparent from the following description, wherein a preferred construction will now be 35 described with reference to the accompanying drawings, in which:—

Fig. 1 is a plan view of my improved device in its closed position,

Fig. 2 is a view of the arrangement shown 40 in Fig. 1 in the open position, and

Fig. 3 is a section on the line 3—3 of Fig. 1.

Referring now to the drawings:—

I provide two light ribbon-like plates of 45 suitable size and shape, the upper plate 1 of

which is slideable upon the lower plate 2 in a

longitudinal direction, and to some extent in a transverse direction, as will hereafter appear. The upper plate 1 is provided with prongs 3 and the lower plate 2 with prongs 4, these prongs being formed of the material of the plate and shaped as shown by a bending operation.

The upper plate 1 is provided with cam slots 5 each having an inclined portion and a longitudinal portion; the lower plate 2 carrying a corresponding number of fixed pins or studs 6 functionally engaging the slots 5, the lower part of each pin passing through the lower plate 2, the binding strip 8, and the reinforcing strip 9, and being secured thereto by a riveting operation, a shoulder 7 being provided on each of the pins 6 whereby this operation may be conveniently effected.

It will of course be understood that if necessary or desirable the binding strip 8 and the reinforcing plate 9 may be dispensed with, in which case the pins 6 would be riveted over the bottom plate 2.

The lower plate 2 is further provided with a guide or stop 10 which in itself forms part of the lower plate. The upper part of each pin 6 is provided with a dome-shaped head, the lower surface of which is in spaced relation to the shoulder upon the pin whereby the upper blade 1 is adapted to slide freely upon the lower plate 2, the prongs being opened by reason of the longitudinal and transverse movement of the plate 1 over the plate 2, due to the upward movement of the plate 1 by means of the thumb-piece 11 on the plate 1.

By constructing my file or loose-leaf book in this way, I provide a device of extremely light yet strong construction and one which is particularly effective for the purpose to which it is to be applied, while the arrangement can be employed with equal effect and like advantage to a binder or loose-leaf book of any size or capacity.

I wish it to be understood that my invention is not to be limited to the precise details of construction hereinbefore described as various modifications may be made therein; for example, the method of forming the coating prongs and also of operating the upper plate

to give the desired relative longitudinal and transverse movement may be effected by any suitable means, all such modifications as these coming within the scope of my invention.

5. What I claim and desire to secure by Letters Patent is:—

1. A device of the kind referred to, comprising a plate, a second plate slidable upon the first and in superposed relation to the lower plate, a plurality of cam slots provided in the upper slidable plate and engaging said pins; whereby the upper plate is slid able in a longitudinal, and, to some extent, in a transverse direction relative to the lower plate, a plurality of cooperating prongs provided on both the upper and lower plate, and a guide formed integral with the lower plate.

2. A device of the kind referred to, comprising a plate, a second plate slidable upon the first and in superposed relation thereto, a plurality of pins fixed to the lower plate, a plurality of cam slots provided in the upper slidable plate and engaging said pins whereby the upper plate is slid able in a longitudinal, and, to some extent, in a transverse direction relative to the lower plate, a plurality of prongs formed integral with the upper plate and a plurality of cooperating prongs formed integral with the lower plate, and a guide formed integral with the lower plate.

3. A device of the kind referred to, comprising a plate, a second plate slidable upon the first and in superposed relation thereto, a plurality of pins fixed to the lower plate, a plurality of cam slots provided in the upper slidable plate and engaging said pins whereby the upper plate is slid able in a longitudinal, and, to some extent, in a transverse direction relative to the lower plate, a plurality of prongs formed integral with the upper plate and a plurality of cooperating prongs formed integral with the lower plate, and a guide formed integral with the lower plate, and manually operated means for effecting the relative movement between the two plates.

In testimony whereof I affix my signature.
GEORGE HERBERT GUYATT.
